UNITED STATES PATENT OFFICE.

ALBERT E. HARRISON, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

PAD FOR FACILITATING MACHINING OF CASTINGS.

1,188,766.

Specification of Letters Patent. Patented June 27, 1916.

Application filed November 30, 1914. Serial No. 875,189.

To all whom it may concern:

Be it known that I, ALBERT E. HARRISON, a citizen of the United States, residing at Milwaukee, in the county of Milwaukee and State of Wisconsin, have invented a certain new and useful Improvement in Pads for Facilitating Machining of Castings, of which the following is a specification.

This invention relates to improvements in the construction of machine elements and particularly to means for facilitating machining of cast machine elements or members.

An object of the invention is to provide means for facilitating machining of castings.

One of the more specific objects is to provide a plurality of local pads for a cast member, the finishing of which pads will provide suitable joining surfaces of coaction with an adjacent member of a completed structure.

Another object is to provide a local pad which may be securely fixed into place within the cast member during the casting operation.

A further object is to provide one or more pads with portions or projections which interlock with adjacent portions of the cast member, and to secure the pad to the cast member by fusion of metal.

Still another object is to provide a relatively soft and readily machinable cast-in pad which may be finished without necessitating finishing of the relatively hard surface of the main casting.

A clear conception of an embodiment of the invention may be had by referring to the drawing accompanying and forming a part of this specification in which like reference characters designate the same or similar parts in the various views.

Figure 1 is a fragmentary sectional view of a pair of machine elements or members showing a cast-in pad in one of the members, the section being taken along the line I—I of Fig. 2. Fig. 2 is a fragmentary end view of one of the machine elements or members showing several of the local cast-in pads. Fig. 3 is an enlarged rear view of one of the pads removed from the casting. Fig. 4 is an enlarged end view of one of the pads removed from the casting.

In machining large castings for certain purposes, such as in crushers, revolving screens and like machines, it has been found

unnecessary to provide a close fit between the entire adjacent surfaces of the assembled structure. It has also been found undesirable to remove only the surface scale of large castings in order to finish the same. The present invention contemplates the elimination of the necessity of finishing the entire surfaces of the castings and also the elimination of the danger of damaging the machine tools during the finishing operation. While the invention is shown as applied to a body of revolution, it should be understood that it is also applicable to bodies having rectilineal elements and to other forms of bodies.

Referring specifically to Figs. 1 and 2, the machine element or member 2 is constructed of cast metal and is provided at its periphery with a series of local soft metal pads 1 preferably made of cast iron. The pads 1 when finished or machined, have curved surfaces 7 and plane surfaces 6 which are adapted to coact with the finished adjacent internal and end surfaces of the member 3 respectively. The members 2, 3, may be any machine elements between which there should be a reasonably close fit when the parts are assembled.

The individual pads, views of one of which are shown in Figs. 3 and 4, have body portions of angular formation and are each provided with a pair of dovetailed projections 4 which are separated by means of a dovetailed recess 8. The projections 4 are united with the adjacent portion of the main body portion by means of cylindrical neck portions 5.

The pads 1 are formed preferably of soft iron either by casting or any other process, so that they may be readily machined without danger of injury to the machine tools. When it is desired to apply the pads 1 to a cast member, the pads 1 are first properly arranged in the mold in the usual manner, after which the metal is cast about them as shown in Figs. 1 and 2. The cast metal enters the spaces between the projections 4 and the main body of the pad, surrounding the neck portions 5, and also filling the recess 8, thereby forming positive interlocking portions on the pad and member for holding the two elements together. During the casting, the metal of the pads 1 will become sufficiently heated to produce welding of the pads to the cast member. It has been found,

however that the welding of the parts alone is not sufficient to produce a joint which is firm enough to prevent displacement of the pads during machining. With the use of 5 dovetailed and interlocking projections on the pads and member, a firm connection which is capable of withstanding strains due to machining is formed. After the pads 1 have been cast into the member 2, the surfaces 6, 7, of the pads may be readily machined to the proper dimensions.

It should be understood that it is not desired to be limited to the exact details of construction shown and described, for obvious modifications will occur to a person skilled in the art.

It is claimed and desired to be secured by Letters Patent,—

1. As an article of manufacture, a pad 20 having a machinable face and having opposite end faces each at an angle to said machinable face and servable as abutments in a casting during machining of said machinable face, and a projection extending 25 transversely of said end faces and interlocking with said casting.

2. As an article of manufacture, a pad having a machinable face and having opposite end faces each at an angle to said machinable face and servable as abutments in 30 a casting during machining of said ma-

chinable face, and a projection extending transversely of said end faces and interlocking with said casting, said projection having a recess therein whereby an additional interlocking is possible between said projection and said casting. 35

3. As an article of manufacture, a pad comprising a body portion having a machinable face and having opposite end faces each at an angle to said machinable face and servable as abutments in a casting during machining of said machinable face, a projection extending transversely of said end faces and interlocking with said casting, and a neck portion connecting said body portion and said projection. 40

4. As an article of manufacture, a pad having an L-shaped cross-section, a dovetailed projection extending from one leg of 50 the L, said projection being spaced from and substantially parallel to the other leg of the L, and a neck portion connecting said projection with the last mentioned leg of said L. 55

In testimony whereof, the signature of the inventor is affixed hereto in the presence of two witnesses.

ALBERT E. HARRISON.
